[57] CLAIM

The ornamental design for a combined shipping and display container for sunglasses or the like, as shown and described.

DESCRIPTION

FIG. 1 is a front perspective view of a combined shipping and display container for sunglasses or the like showing my new design;

FIG. 2 is a front perspective view thereof, similar to FIG. 1 in partially open position;

FIG. 3 is a rear perspective view thereof;

FIG. 4 is a rear perspective view thereof, similar to FIG. 3 in partially open position;

FIG. 5 is an exploded view thereof; and

FIG. 6 is a bottom perspective view thereof.

*Fig. 1**Fig. 2*

*Fig. 3**Fig. 4*
